FIG. - 2

John Sneed Inventor

By Bates, Macklin, Gorlick & Teare

Attorneys

UNITED STATES PATENT OFFICE

JOHN SNEED, OF FERNDALE, MICHIGAN, ASSIGNOR TO THE MIDLAND STEEL PRODUCTS COMPANY, OF CLEVELAND, OHIO, A CORPORATION OF OHIO

BRAKE

Application filed October 4, 1928. Serial No. 310,267.

This invention relates to vehicle brakes and more particularly to a brake of the auxiliary servo shoe type wherein the manually applied or directed force is directed to an auxiliary shoe, which auxiliary shoe acts as the expanding means for the main friction element or elements.

In my copending application, Serial No. 223,020, filed September 30th, 1927, I have illustrated this general type of brake and my present invention constitutes an improvement upon the former invention particularly in structure and arrangement of parts. It is among the objects of my invention to provide a brake of simple construction, comprising few easily assembled parts. Another object is to simplify the arrangement of the auxiliary shoe with relation to the anchor pin and the ends of the main shoe. Another object is to arrange like end parts for the main shoe of which the body parts are substantially different. Another object is to devise an auxiliary shoe readily cooperable with a simple operating mechanism.

Other objects will appear from the following description of a preferred form of my invention, reference being had to the accompanying drawings. The essential characteristics are summarized in the claims.

In the drawings, Fig. 1 is an elevation of the assembly including the main and auxiliary shoes and Fig. 2 is a section taken along the lines 2—2 of Fig. 1.

Referring to the drawings, I have illustrated in my brake the usual brake drum D, the open face of which is closed by an apron A, which apron carries by means of a bracket B an anchor pin P. Supported by the apron and held out of contact with the drum when idle, is a brake shoe S carrying suitable friction material L. The shoe S may comprise a relatively rigid channel part 1 and a relatively flexible band like part 2 joined together as at 3. The end of the band like part 2 has a channel shaped part 4 secured to it so that both ends of the shoe are similar.

Referring also to Fig. 2, the ends of the side flanges of the channel shaped parts are

notched to present arcuate anchor engaging surfaces 5 so that as either end of the shoe is forced away from the anchor, in the application of the brake, the other end may swing and pivot about the axis of the anchor pin. In the mid portion of the shoe and opposite the anchor, I provide an adjustable spring centering means 6 similar to that illustrated in my copending application Serial No. 281,062 filed May 28th, 1928. Briefly stated, this centering device comprises a pair of springs 7 and 8 having their remote ends secured to the body of the shoe as at 9 and 10 and having their near end secured to a plate 11, which is adjustably clamped to the apron.

To operate the brake, I provide an auxiliary shoe 20, see also Fig. 2, which is formed in a modified T-section by securing a pair of channels 21 and 22 back to back by such means as welds 23. The shoe carries suitable friction material L' along the part comparable to the head of the T and has at the base of the T a smooth arcuate roller or cam engaging surface 24. The body of the shoe may be apertured as at 25 to encompass the anchor pin and to be free to move in all directions relative to the anchor pin within the greatest limits of its travel in operation.

The webs of the channeled ends of the main shoe are inclined radially inward as at 30 and each of these webs are slotted circumferentially as at 31, see also Fig. 2, to receive the body of the auxiliary shoe. When the shoes are in idle position, the ends of the auxiliary shoe are adjacent the bottoms or ends of the slots in the end of the main shoe as at 32 but preferably out of contact therewith so that the both ends of the main shoe may be drawn against the anchor pin in idle position.

Joining the ends of the auxiliary shoe and parts near the ends of the main shoe, are retractor springs 40 and 41, which hold the ends of the main shoe upon the anchor and which draw the auxiliary shoe radially inward until it rests, at least at its ends, upon the webs of the channeled ends of the main shoe as at 33. Thus in idle position all of

the parts are snugly held together and rattling is avoided.

To operate the brake, the auxiliary shoe is moved radially into engagement with the drum whereupon it is carried by contact with the drum in the direction of drum rotation, and as the auxiliary shoe is carried by the drum, it engages one or the other of the ends of the main shoe thereby forcing the main shoe into wrapping engagement with the drum. To move the auxiliary shoe radially, I provide a roller or similar means eccentrically carried by a shaft 51 which is journaled in the bracket B and has a rigidly fixed operating arm 52, which may be actuated by suitable well known means not illustrated herein.

It suffices to say that forces tending to rotate the shaft 51 may be applied through the arm 52 to rotate the shaft counter-clockwise as viewed in Fig. 1 to raise the roller 50 and thereby move the auxiliary shoe radially outward and upwardly as viewed in Fig. 1. The roller engages the smooth lower surface 24 of the base of the auxiliary shoe and through the roller a radial pressure is maintained while the auxiliary shoe is carried circumferentially away from its idle position by contact with the drum.

From the foregoing, it will appear that a brake according to my invention is simple in construction; that the arrangement of the auxiliary shoe and its disposition adjacent the anchor pin and its interfitting relation with the ends of the main shoe and is eminately simple and rugged; that the parts comprising my brake are few in number and of character that is adapted to quantity production; and that the assembly of the parts may be quickly and easily accomplished.

While I have illustrated and described a preferred form of my invention, various modifications will appear to those skilled in the art all within its scope, and I do not care to be limited in this or any manner other than by the claims appended hereto.

I claim:

1. In a brake, the combination of a friction device having oppositely disposed adjacent channel shaped ends, an auxiliary shoe arranged to act on either of the ends of said device having a lining supporting part overlying the ends thereof and having an inwardly extending reinforcing part disposed between the side flanges of the said ends.

2. In a brake, the combination of a main shoe having adjacent channel shaped ends, an auxiliary shoe arranged to act on either of the ends of the main shoe having a lining supporting part overlying the ends of first named shoe and having an inwardly extending reinforcing part disposed between the side flanges of the ends of the main shoe.

3. In a brake, the combination of a main

shoe having an arcuate lining supporting part and an extension thereof with spaced radial flanges, an auxiliary shoe having a lining supporting part overlying said extension and having a radial flange disposed 70 between the flanges thereof.

4. In a brake, the combination of a main shoe having an arcuate lining supporting part and an extension thereof with spaced radial flanges, an auxiliary shoe having a lining supporting part overlying said extension of the main shoe and having a radial flange bisecting said extension and disposed 75 between the flanges thereof.

5. In a brake, the combination of a main shoe having channeled portions at its ends with a circumferentially extending web and inwardly extending radial side flanges, said web being circumferentially slotted, and an auxiliary shoe having an inwardly extending reinforcing flange parallel and spaced 80 between said side flanges and disposed within the slot in said web and engaging the end of the slot of said web to move said shoe.

6. In a brake, the combination of a main shoe having a channelled portion at its ends with a circumferentially extending web and radially extending side flanges, said web being centrally slotted, and an auxiliary shoe 95 having a centrally disposed inwardly extending reinforcing flange disposed within the slot in said web and engaging the end of the slot of said web to move said shoe.

7. In a brake, the combination of a main friction element including a curved band like part, a channel shaped part secured at the end of the band like part and extending beyond the end thereof and having its web notched or slotted circumferentially to receive and guide at least a part of an adjacent shoe.

8. In a brake, the combination of a main friction element including a curved band like part, a channel shaped part secured at the end of the band like part and extending beyond the end thereof and having its web diverted inwardly from a continuation of the arc of the band like part and having its web notched or slotted circumferentially to receive and guide an adjacent shoe.

9. A brake including a shoe having an arcuate lining supporting part with an integrally formed portion extending beyond the lining supporting part, said portion being 110 circumferentially notched or slotted to receive a radially disposed member through which expanding forces may be delivered to the shoe.

10. A brake including a shoe having an arcuate lining supporting part with an integrally formed portion extending beyond the lining supporting part and inclined inwardly from a continuation of the arc of the lining supporting part, said portion being 125 130

circumferentially notched or slotted, in combination with a T-shaped shoe having a radial part lying in the notch or slot and having a lining supporting part overlying the inwardly inclined portion.

11. In a brake, the combination of an anchor pin, a friction element having end parts engageable with said anchor pin at least in idle position, and a shoe having a body part encompassing said anchor pin and engageable with at least one of the end parts of said friction element to move it from the anchor pin when the brake is applied.

12. In a brake, the combination of an anchor pin, a friction element having end parts engageable with said anchor pin, at least in idle position and a shoe having a body part freely encompassing said anchor pin and engageable with either of the end parts of said friction element to move one of them from the anchor pin when the brake is applied depending upon the direction of drum rotation.

13. In a brake, the combination of a friction device having end parts, an anchor pin disposed between said end parts, an auxiliary shoe having an inwardly extending radial flange, said flange being apertured to freely encompass said anchor pin and means for forcing said auxiliary shoe into engagement with the drum and into engagement with at least one of said end parts of the friction element.

14. In a brake, the combination of an anchor pin a substantially annular main shoe having axially spaced end parts engaging the anchor pin at least in idle position, and an auxiliary servo shoe overlying the anchor pin and having an inwardly extending part lying between the said axially spaced end parts of the main shoe.

15. In a brake, the combination of an anchor pin, a substantially annular main shoe having axially spaced end parts engaging the anchor pin at least in idle position, an auxiliary servo shoe overlying the anchor and having an inwardly extending part lying between the said axially spaced end parts of the main shoe and means including an eccentrically mounted roller engaging the said inwardly extending part of the auxiliary servo shoe for moving it radially into engagement with the brake drum and for maintaining a radial pressure while the auxiliary servo shoe moves circumferentially relative to the anchor pin.

16. In a brake the combination of an apron, a bracket secured thereto, an anchor pin carried by the bracket, a rotatable shaft journalled in the bracket, a roller eccentrically mounted on said shaft, a brake shoe having an inwardly extending apertured part encompassing said anchor and engageable with said roller and movable radially into

engagement with the brake drum and means for rotating said shaft to cause said roller to engage said shoe.

17. A brake according to claim 16 having a second shoe with at least one end engageable with said anchor in idle position and engageable with said first named shoe to be forced away from said anchor into engagement with the brake drum when said first named shoe is carried circumferentially by contact with the brake drum.

18. In a brake, the combination of an apron, a bracket secured thereto, an anchor pin carried by the bracket, a rotatable shaft journalled in the bracket, a roller eccentrically mounted on said shaft, a T-shaped brake shoe having an inwardly extending apertured part encompassing said anchor and engageable by said roller and movable radially into engagement with the brake drum.

19. A brake according to claim 18 having a shoe with opposite ends engageable with said anchor at least in idle position and engageable with said first named shoe to be forced away from said anchor into engagement with the brake drum when said first named shoe is carried circumferentially by contact with the brake drum according to the direction of drum rotation.

In testimony whereof, I hereunto affix my signature.

JOHN SNEED.
